(57) **CLAIM**

The ornamental design for a double loop toe corrector, as shown and described.

DESCRIPTION

FIG. 1 is a front view of a double loop toe corrector of the present design;

FIG. 2 is a first side view of the double loop toe corrector of the design of FIG. 1;

FIG. 3 is a second view of the double loop toe corrector of the design of FIG. 1;

FIG. 4 is a top view of the double loop toe corrector of the design of FIG. 1;

FIG. 5 is a bottom view of the double loop toe corrector of the design of FIG. 1; and,

FIG. 6 is a rear view of the double loop toe corrector of the design of FIG. 1.

In the drawing, the broken lines show portions of a double loop toe corrector that form no part of the claim.
